UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

DROP DOOR FOR RAILWAY CARS.

Application filed September 1, 1927. Serial No. 216,963.

The invention relates to a railway dump car having a "door" forming a part of the car for retaining the load therein which door is provided with hinges adjacent one of its edges and is capable of being "dropped" or swung open so that the load in discharging slides or passes over the upper surface of the door. Any means of raising the door to the closed position and any means for locking and releasing the door may be employed with my device.

A door for this purpose must be very strong and durable because:

First, it is a part of the floor of the car and as such must sustain the load as well as the impact blow of the load when the car is in motion. Second, the car is frequently loaded from chutes or tipples from a height of ten feet or more, causing the load to be dropped directly upon the doors. Third, clam shell buckets are frequently used to unload such cars and it is not uncommon for these buckets to rest upon and drag over the doors. Fourth, when the door suddenly comes to rest after being dropped, it is not only subjected to a severe shock but it must sustain the severe impact thrust of the load which of course follows the door. Fifth, as the load is theoretically equally distributed, the door must be strong over its entire area and must be capable of transmitting the resulting stresses to the car body without much deflection and no substantial distortion. Any bending of the door or drooping of the corners would cause a leak of the lading, especially of such fine material as sand, chats, etc. Any bending or warping might interfere with the complete closing and locking of the door.

As it costs as much to haul a ton of car as it does to haul a ton of paying freight, it is imperative that the car and any part thereof be as light as possible. Furthermore, the total weight of the car and freight is determined by the strength of certain standard axles, so that the lighter the car the greater amount of freight a given car will be allowed to carry.

An object is to form a metallic door with integral corrugations or ribs which impart to it a certain amount of strength and rigidity to resist loads imposed thereon and

to so form the ends of the corrugations or ribs as to provide a certain amount of resiliency to enable the door to deflect and return to its normal position without appreciable amount of permanent distortion. 55

Another object is to form and arrange a plurality of corrugations in a metallic door so as to obtain a desired proportion 60 between strength, rigidity and resiliency.

Another object is to obtain this result with the least amount of raw material and to provide a finished article of the least possible weight consistent with strength requirements. 65

Another object is to obtain the desired strength, rigidity and resiliency by forming a hopper door of a metallic plate with integral corrugations or ribs which taper in 70 width toward their opposite ends and other preferably alternate corrugations or ribs which project in the opposite direction therefrom and which increase in width toward their opposite ends, the opposite ends of 75 the last mentioned corrugations being formed to provide a certain amount of resiliency to enable the plate to deflect and return to its normal position without appreciable permanent distortion. 80

Another object is to form a hopper door of a metallic plate with a plurality of corrugations which are all of the same depth and of equal depth for the major portion of their length so as to form a substantially flush surface on one side of the plate and to also form the plate with corrugations positioned preferably alternately therebetween which are deepest adjacent their middle and decrease in depth toward their opposite ends. Another object is to merge the adjacent portions of the oppositely projecting corrugations into each other so as to provide, in effect, a plurality of corrugations having a depth equal to the total depth 95 of the oppositely projecting corrugations. 85

Another object is to provide such a corrugated metallic door which can be formed by pressing it (when heated, if necessary) between dies which move toward each other 100 in one direction only.

The advantages of my door are applicable to any door of a freight car, such as drop bottom general service cars (used

in the drawings), hopper cars, swinging side doors or hopper bottom coal cars, etc.

In the drawings:

Fig. 1 shows a portion of a railway car 5 with my device applied thereon.

Figs. 2 and 3 are sections on line 2—2 and line 3—3 respectively of Fig. 1.

Figs. 4 and 5 are sections on line 4—4 and line 5—5 respectively of Fig. 1 with the car 10 parts omitted.

Figs. 6, 7 and 8 are sections similar to Figs. 3, 4, and 5 but show the major corrugations with an arcuate configuration.

To illustrate one adaptation of my device, I have shown a so-called "general service" drop bottom gondola car wherein the major portion of the floor consists of drop doors. The door openings are surrounded by the center construction, side wall and 20 cross diaphragms. In normal or closed position the door completely closes this opening and in fact is a trifle larger on all sides than the opening so as to provide a lap joint between the door and the car frame 25 members. The doors are hinged to the center construction and are supported adjacent the side wall by the raising or locking mechanism. Any convenient stop may be used to limit the downward movement of the 30 door.

The plate is formed of integral corrugations or ribs 2 (called embossments) and 3 (called depressions) projecting alternately in opposite directions (upwardly and downwardly) and preferably having their sides 4 merging into the adjacent corrugations so as to provide, in effect, a plurality of parallel corrugations having a depth equal to the total depth of the oppositely projecting 40 corrugations. For a space 6 equi-distant on each side of their middle the corrugations are spaced apart distances equal to their widths so that the neutral axis of the corrugated section is midway between the bounding 45 planes of the corrugated structure. The apices 7—8 of the corrugations are preferably arched so as to transmit any load imposed upon them to the opposite side walls 4 of the corrugations. This arched formation has the further advantage of reducing the stretch of the metal in pressing the corrugations in the plate. I have used the terms "embossments" and "depressions" in the specification and claims to avoid confusion and differentiate between the corrugations projecting one way from the original plane 9 of the plate and those projecting in the opposite direction thereto, but otherwise I contemplate no difference in the meaning 55 of the terms.

In the construction illustrated the embossments 2 have a constant width and depth for a space 6 equi-distant on each side of the middle of the plate and then decrease in width (and preferably also in depth) until

they merge into the original plane 9 of the plate.

The depressions 3 are preferably positioned alternately between the embossments 2 and preferably have a constant width and depth 70 for a space 6 equi-distant on each side of the middle of the plate corresponding to embossment 2 and then preferably maintain a constant depth but increase in width toward their opposite ends proportionately to the 75 decrease in width of the embossments so that the adjacent sides 4 of the embossments and depressions are parallel, and in the preferred form, these sides merge into each other for substantially the entire length of these elements.

The extremities of the depressions 3 are split or divided to form ribs 11 which decrease in depth and also preferably in width toward the middle of the depressions. 85 The embossments, depressions and ribs merge into each other adjacent their extremities so as to form a sinuous configuration, as shown in Figs. 5 and 8, wherein the several divided portions 12 of the depressions are spaced apart distances equal to their width so that the neutral axis is midway between the bounding planes of the corrugated structure. The depressions are provided with terminal portions which 95 merge into the original plane of the plate.

The various contours of the corrugations are such that the lengths of the center lines of the metal at all cross sections of the corrugated portion of the plate normal to the 100 corrugations are equal. Furthermore, the metal is so disposed as to provide the required strength at any cross section thereof to sustain an equally distributed load.

Fig. 4 shows the embossments 2, depressions 3 and the ribs 11 which bifurcate the depressions at their opposite ends.

The embossments and depressions may be of equal depth or one group may be deeper than the other group to suit conditions. In 110 the form illustrated the embossments are shallower than the depressions.

Figs. 3, 4 and 5 show the depressions and embossment with flat apices forming a truncated configuration and Figs. 6, 7 and 115 8 show a modified form wherein the depressions and embossments have arcuate apices forming a sinuous configuration.

It is understood that the embossments or corrugations may extend normally like to 120 those illustrated in the drawings, or even diagonally, and still come within the scope of the invention and, furthermore, while I have described and claimed a single plate, it is understood that the door may be made 125 of a plurality of united plates and still come within the scope of the invention.

The marginal portion 9 (or portions) may be provided with flanges so as to further stiffen the sides of the door against deflec- 130

tion under load and to stiffen the entire door against buckling or distortion.

This is a continuation in part of my application Serial No. 120,732, filed July 6, 1926, 5 wherein I have disclosed and claimed broadly the particular formation of a metallic plate and specifically the use of such a structure as a wall for a railway car, and in my co-pending application Serial No. 216,964, 10 filed September 1, 1927 (also a continuation in part of my application Serial No. 120,732, filed July 6, 1926,) I have specifically disclosed and claimed the use of such a structure as a side door for a railway car. 15 The accompanying drawings illustrate the preferred form of the invention, though it is to be understood that the invention is not limited to the exact details of construction shown and described, as it is obvious that 20 various modifications thereof within the scope of the claims will occur to persons skilled in the art.

I claim:

1. In a railway car having a door opening, 25 a door hinged adjacent one edge thereof and supported at the opposite edge thereof, said door comprising a metallic plate provided with a plurality of embossments decreasing in width toward their ends and 30 terminating within the plate adjacent opposite edges of the door and a plurality of depressions increasing in width toward their ends and terminating within the plate adjacent opposite edges of the door, said embossments and 35 depressions projecting in opposite directions from the original plane of the plate.
2. In a railway car having a door opening, 40 a door hinged adjacent one edge thereof, and supported at the opposite edge thereof, said door comprising a metallic plate provided with a plurality of embossments decreasing in width toward their ends and 45 terminating within the plate adjacent opposite edges of the door and a plurality of depressions increasing in width toward their ends and terminating within the plate adjacent opposite edges of the door, said embossments and 50 depressions projecting in opposite directions from the original plane of the plate, the ends of the depressions being divided to form ribs.
3. In a railway car having a door opening, 55 a door hinged adjacent one edge thereof, and supported at the opposite edge thereof, said door comprising a metallic plate provided with a plurality of embossments decreasing in width toward their ends and 60 terminating within the plate adjacent opposite edges of the door and a plurality of depressions increasing in width toward their ends and terminating within the plate adjacent opposite edges of the door, said embossments and 65 depressions projecting in opposite directions from the original plane of the plate,

the ends of the depressions being divided to form ribs, said embossments, ribs and divided portions of the depressions all being the same with adjacent said opposite edges.

4. In a railway car having a door opening, 70 a door hinged adjacent one edge thereof and supported at the opposite edge thereof, said door comprising a metallic plate provided with a plurality of embossments decreasing in width toward their ends and 75 terminating within the plate adjacent opposite edges of the door and a plurality of depressions increasing in width toward their ends and terminating within the plate adjacent opposite edges of the door, said embossments and 80 depressions projecting in opposite directions from the original plane of the plate, the ends of the depressions being divided to form ribs, said embossments and 85 depressions being equal in width adjacent their medial line.

5. In a railway car having a door opening, 90 a door hinged adjacent one edge thereof and supported at the opposite edge thereof, said door comprising a metallic plate provided with a plurality of embossments decreasing in width toward their ends and 95 terminating within the plate adjacent opposite edges of the door and a plurality of depressions increasing in width toward their ends and terminating within the plate adjacent opposite edges of the door, said embossments and 100 depressions projecting in opposite directions from the original plane of the plate, the ends of the depressions being divided to form ribs, said embossments and 105 depressions being equal in width and of constant width equi-distant on opposite sides of the medial line.

6. In a railway car having a door opening, 105 a door hinged adjacent one edge thereof and supported at the opposite edge thereof, said door comprising a metallic plate provided with a plurality of embossments decreasing in width toward their ends and 110 terminating within the plate adjacent opposite edges of the door and a plurality of depressions positioned alternately therewith increasing in width toward their ends and terminating within the plate adjacent opposite edges of the door, said embossments and 115 depressions projecting in opposite directions from the original plane of the plate, the ends of the depressions being divided to form ribs with the sides of the embossments merging into the adjacent sides of 120 the depressions.

7. In a railway car having a door opening, 125 a door hinged adjacent one edge thereof and supported at the opposite edge thereof, said door comprising a metallic plate provided with a plurality of embossments decreasing in width toward their ends and 130 terminating within the plate adjacent opposite edges of the door and a plurality of

depressions positioned alternately therewith increasing in width toward their ends and terminating within the plate adjacent opposite edges of the door, said embossments and depressions projecting in opposite directions from the original plane of the plate, the ends of the depressions being divided to form ribs with the sides of the embossments merging into the adjacent sides of the depressions for substantially the entire length of these elements.

8. In a railway car having a door opening, a door hinged adjacent one edge thereof and supported at the opposite edge thereof, said door comprising a metallic plate provided with a plurality of embossments decreasing in width and in depth toward their ends and terminating within the plate adjacent opposite edges of the door and a plurality of depressions increasing in width toward their ends and terminating within the plate adjacent opposite edges of the door, said embossments and depressions projecting in opposite directions from the original plane of the plate, the ends of the depressions being divided to form ribs.

9. In a railway car having a door opening, a door hinged adjacent one edge thereof and supported at the opposite edge thereof, said door comprising a metallic plate provided with a plurality of embossments decreasing in width toward their ends and terminating within the plate adjacent opposite edges of the door and a plurality of depressions of constant depth the major portion of their length and increasing in width toward their ends and terminating within the plate adjacent opposite edges of the door, said embossments and depressions projecting in opposite directions from the original plane of the plate, the ends of the depressions being divided to form ribs.

10. In a railway car having a door opening, a door hinged adjacent one edge thereof and supported at the opposite edge thereof, said door comprising a metallic plate provided with a plurality of embossments decreasing in width toward their ends and terminating within the plate adjacent opposite edges of the door and a plurality of depressions positioned alternately therewith of constant depth the major portion of their length and increasing in width toward their ends and terminating within the plate adjacent opposite edges of the door, said embossments and depressions projecting in opposite directions from the original plane of the plate, the ends of the depressions being divided to form ribs.

11. In a railway car having a door opening, a door hinged adjacent one edge thereof and supported at the opposite edge thereof, said door comprising a metallic plate provided with a plurality of embossments de-

creasing in width toward their ends and terminating within the plate adjacent opposite edges of the door and a plurality of depressions positioned alternately therewith of constant depth the major portion of their length and increasing in width toward their ends and terminating within the plate adjacent opposite edges of the door, said embossments and depressions projecting in opposite directions from the original plane of the plate, the ends of the depressions being divided to form ribs, said embossments, ribs and divided portions of the depressions all being the same width adjacent said opposite edges, said embossments and depressions being equal in width adjacent their medial line with the sides of the embossments merging into the adjacent sides of the depressions for substantially the entire length of these elements.

12. In a railway car having a door opening, a door hinged adjacent one edge thereof and supported at the opposite edge thereof, said door comprising a metallic plate formed with a plurality of embossments which decrease in depth toward their opposite ends and terminate within the plate adjacent opposite edges of the door, said plate also formed with a plurality of depressions of constant depth the major portion of their length and terminating within the plate adjacent said opposite edges of the door, said embossments and depressions projecting in opposite directions from the original plane of the plate.

13. In a railway car having a door opening, a door hinged adjacent one edge thereof and supported at the opposite edge thereof, said door comprising a metallic plate formed with a plurality of embossments which decrease in depth toward their opposite ends and terminate within the plate adjacent opposite edges of the door, said plate also formed with a plurality of depressions positioned alternately therebetween of constant depth the major portion of their length and terminating within the plate adjacent said opposite edges of the door, said embossments and depressions projecting in opposite directions from the original plane of the plate.

14. In a railway car having a door opening, a door hinged adjacent one edge thereof and supported at the opposite edge thereof, said door comprising a metallic plate formed with a plurality of embossments of constant depth for a short distance adjacent their middle which decrease in depth toward their opposite ends and terminate within the plate adjacent opposite edges of the door, said plate also formed with a plurality of depressions of constant depth the major portion of their length and terminating within the plate adjacent said opposite edges of the

door, said embossments and depressions projecting in opposite directions from the original plane of the plate.

15. In a railway car having a door opening, a door hinged adjacent one edge thereof and supported at the opposite edge thereof, said door comprising a metallic plate formed with a plurality of corrugations projecting in opposite directions from the original plane 10 of the plate, some of which have their opposite ends divided so as to provide a relatively rigid structure adjacent the middle of the door and a relatively resilient structure adjacent opposite edges of the door.
- 15 16. In a railway car having a door opening, a door hinged adjacent one edge thereof and supported at the opposite edge thereof, said door comprising a metallic plate formed 20 with a plurality of corrugations projecting in opposite directions from the original plane of the plate, some of which have their opposite ends divided so as to provide a relatively rigid structure adjacent the middle of the door which gradually becomes a relatively 25 resilient structure adjacent opposite edges of the door.

17. In a railway car having a door opening, a door hinged adjacent one edge thereof and supported at the opposite edge thereof,

said door comprising a metallic plate formed 30 with a plurality of corrugations projecting in opposite directions from the original plane of the plate which are relatively deep adjacent their middle portions, some of which have their opposite ends divided to 35 form a greater number of relatively shallow corrugations adjacent their end portions so as to provide a relatively rigid structure adjacent the middle of the door and a relatively 40 resilient structure adjacent the opposite edges of the door.

18. In a railway car having a door opening, a door hinged adjacent one edge thereof and supported at the opposite edge thereof, said door comprising a metallic plate formed 45 with a plurality of corrugations projecting in opposite directions from the original plane of the plate which are relatively deep and relatively wide adjacent their middle portions, some of which have their opposite 50 ends divided to form a greater number of relatively shallow and relatively narrow corrugations adjacent their end portions, so as to provide a relatively rigid structure adjacent the middle of the door and a relatively 55 resilient structure adjacent the opposite edges of the door.

ARTHUR E. SMALL.
